(57) **CLAIM**

The ornamental design for a combined hammock stand and hand cart, substantially as shown and described.

DESCRIPTION

FIG. 1 is a perspective view of a combined hammock stand and hand cart, showing our new design.

FIG. 2 is a perspective view in extended condition.

FIG. 3 is perspective view converted to a hand cart.

FIG. 4 is a front perspective view of the hammock stand.

FIG. 5 is a left perspective view thereof.

FIG. 6 is a top perspective view thereof.

FIG. 7 is a bottom perspective view thereof.

FIG. 8 is a perspective view in partially folded condition.

FIG. 9 is enlarged fragmentary perspective view showing the top end of the hammock stand.

FIG. 10 is an enlarged fragmentary perspective view showing the bottom center thereof; and,

FIG. 11 is a front perspective view converted to a hand cart. The broken line showings of a turnbuckle in FIGS. 1-8 and 11; a cross bar in FIGS. 1-8 and 11; and a u-bolt in FIGS. 2-7 and 11 are for the purposes of illustrating environmental structure and form no part of the claimed design.

The combined hammock stand and hand cart is a structural support for a hammock and a handcart for moving of the hammock.
